DESIGN FOR A QUILT OR THE LIKE

Application filed October 1, 1929. Serial No. 32,902. Term of patent 3½ years.

To all whom it may concern:

Be it known that I, VIRGINIA HAMILL, a citizen of the United States of America, and a resident of the borough of Manhattan, city, county, and State of New York, have invented a new, original, and ornamental Design for a Quilt or the like, of which the following description, in connection with the accompanying drawing, is a specification.

The figure of the drawing is a plan view of

a quilt showing my new design, in which the puckered border continues entirely about the quilt and the floral decoration shown in detail in the two upper left-hand blocks is repeated in all of the blocks.

I claim as my invention:

The ornamental design for a quilt or the like, substantially as shown and described.
